UNITED STATES PATENT OFFICE.

ERWIN W. SEEGER, OF MILWAUKEE, WISCONSIN, ASSIGNOR TO SEEGER MANUFACTURING COMPANY, OF CHICAGO, ILLINOIS, A CORPORATION OF ILLINOIS.

STOVE.

1,348,588.

Specification of Letters Patent. Patented Aug. 3, 1920.

Application filed January 15, 1917. Serial No. 142,417.

To all whom it may concern:

Be it known that I, ERWIN W. SEEGER, a citizen of the United States, residing at Milwaukee, in the county of Milwaukee and 5 State of Wisconsin, have invented a certain new and useful Improvement in Stoves, of which the following is a full, clear, concise, and exact description, reference being had to the accompanying drawings, forming a 10 part of this specification.

My invention relates to stoves and has for its object the provision of a stove which is adapted in its preferred form more particularly for heating small inclosures such as 15 garages. My invention contemplates the provision of such a stove having in connection therewith automatic means for regulating the degree of heat given off by the stove.

20 In accordance with the preferred form of my invention I utilize a stove which is provided with an inclosing shell longitudinally thereof, the cold air entering the bottom of this shell and emerging at the top 25 thereof, the regulating means being controlled by suitable appliances susceptible to the degree of heat of the air between this inclosing shell and the stove. In other words, the stove heats the air as it is passing 30 through a duct and the temperature of the air in the duct controls suitable appliances to regulate the heating effect of the stove.

My invention contemplates in its preferred form a stove of this character in 35 which the stove may be placed within the compartment or inclosure which it is to heat, and also contemplates a structure in which the interior of the duct aforesaid has no connection with the active fire or flame 40 portion of the stove, the stove being placed preferably exteriorly of the compartment. The duct then at its lower portion extends into the compartment and then again opens up into the compartment at the top thereof 45 so that a circulation of air is caused by virtue of which cold air is drawn from the bottom of the compartment, this air being heated in the duct and then led in the top of the compartment in a heated condition, 50 the stove which projects into this duct for heating the air being so associated with the duct shell that no portion of the flame or fire of the stove is in communication with the interior of the compartment. This is of 55 a special advantage in connection with

garages where the presence of an active flame or fire might cause explosions when gasolene fumes are present therein.

I will explain these two forms which my invention may take more in detail by referring to the accompanying drawings, in which—

Figure 1 is a side view of my improved stove showing the inclosing shell partly in section;

Fig. 2 is a sectional view of the stove and shell along a plane at right angles to the plane of the paper when taken in connection with Fig. 1;

Fig. 3 is a top view of my improved stove;

Fig. 4 is an enlarged detail view showing the regulating mechanism;

Fig. 5 is an enlarged fragmentary view showing the manual control mechanism;

Fig. 6 is a side view partly in section 75 showing my stove as applied exteriorly of the compartment which it is to heat, and

Fig. 7 is a front view of the stove structure shown in Fig. 6.

Referring more particularly to the structure shown in Figs. 1 and 5 inclusive, I have a stove 1 that is provided preferably with a magazine 2, which magazine is closed by the cover or lid 3, the stove having at its lower portion a grate 4 over the ash compartment 80 5. The stove has at its lower portion a mouth 6 through which the ashes may be removed, this mouth being covered by a screen 7 normally when the ashes are not being removed to prevent ignition of any 90 gases which might be in the compartment within which the stove is placed. This mouth is covered by the ash pit door 8 and the opening of this door 8 of course controls the duct in connection with other devices 95 presently to be explained, as is customary in the art. A suitable chain 9 connects this door with the control appliances, as will presently appear. The stove has at its upper extremity a stack 10 through which the products of combustion pass, this stack being provided with a suitable damper 11 adapted to control the heating effect of the stove, this damper 11 being connected through the agency of a suitable link 12 with the control 100 appliances to be presently explained. The stove in its entirety as thus explained is surrounded by a shell 13, which shell is rounded at the top as shown at 14. This shell may be

preferably supported upon legs 15. The 110

shell thus is open at the bottom and open at the top, forming an annular chamber about the stove for heating the air within this chamber. The cold air of course enters at 5 the bottom, is heated, and then leaves the duct or annular chamber at the top in its heated condition. The degree of heating effect of the stove is controlled by the temperature of the air within this duct, and a 10 suitable point is selected, which in this instance happens to be the upper portion of this shell 13; there being placed in the rounded portion 14 a suitable pipe 16, which pipe may be filled with fluid of suitable 15 character, air being used in one of the forms of the invention. The air or other fluid in this pipe 16 expands and contracts in accordance with the temperature of the air passing through the annular chamber be- 20 tween the stove and the shell 13. The object of thus controlling the operations of the stove is due to this, that in compartments of the type specified, it is not so necessary to keep the temperature of the compartment 25 at a certain given amount as it is to keep the compartment heated at least a certain number of degrees above the outside temperature. Compartments such as those under discussion are seldom kept at a seventy de- 30 gree temperature when the air outside is at zero. If the regulator were set and controlled by the temperature of the room then the stove would very rapidly burn itself out under conditions of zero temperature out- 35 side of the compartment.

It is thus desirable to control the operations of the stove in such manner that the stove will not be unduly drafted even though the outside temperature is extremely low. 40 To control this regulating effect the pipe which extends throughout the entire arc of the circle has at one point in its surface an opening which is preferably provided through the agency of a T connection 17. 45 The lower portion of this T connection communicates with the interior of a duplex expandable and retractable diaphragm 18. The two other arms of this T connection engage the two free extremities of this circular 50 pipe. Thus the entire expanding effect of the air or other fluid throughout the entire length of pipe finds expression through the lower portion of the T 17 into the expandable and retractable diaphragms 18. The lower 55 diaphragm is of course closed but is provided with a lug 19, which lug through the agency of a cooperating lug 20 engages a lever 21. The lugs 19 and 20 are screw threaded and have a right and left handed 60 screw thread respectively. A union 22 when turned in opposite directions therefor brings the lugs 19 and 20 either close together or farther apart. This union is carried by a spur gear 23 which meshes with another gear 24, this gear 24 being mounted upon a

spindle 25, the spindle being suitably rotated and operated by the handle 26 to thus control the relative positions of the lugs 19 and 20. As the air or other fluid expands in the tube 16 it presses the lug 19 downwardly on account of the expansion of the diaphragms 18 and thereby pushes the lever 21 (Fig. 4) in a clockwise direction, this lever being pivoted upon the spindle 27. When the air contracts, the lug 19 is raised 75 as the diaphragms 18 contract, thus swinging the lever 21 in a contra clockwise direction. This lever 21 is directly associated with the chain 9. There is a further lever 28 which is also pivoted on the spindle 27, 80 this lever 28 moving synchronously with the lever 21. This lever 28 is connected to the link 12. Brackets 29 support the spindle 27 which supports the levers.

The shell 13 has a projection 30 longitudinally thereof which incloses the various projecting parts, thus to maintain a continuity of the duct. In order to counter-balance the weight of the door 8 and the levers 21 I utilize a leaf spring 31 whose tension is regulated by the wing nut 32, this wing nut co-operating with the curved surface 33 to hold this spring 31 in any desired position to effect its counter-balancing function. The operation of the levers then controls the position of the check damper 11 and the ash pit door 8. Of course, any other suitable instrumentalities might be controlled which might control the degree of combustive effect of the stove. 100

In Figs. 6 and 7, I show a stove regulatable similarly to that shown herein, the various parts being denominated by the same reference characters. The stove 1 again is placed within a duct consisting of the shell 105 13^a. This shell is so arranged that the charging door 34 of the stove projects outwardly of the shell so that the stove may be supplied with fuel without having the flame or fire portion communicate with the interior 110 of the said shell 13^a. The stove and shell are placed in a small shed 35 adjacent a garage or other compartment 36. The shell 13^a then has a mouth 37 at its lower extremity which projects into the compartment 115 36, the mouth being covered by a screen 38 to guard against any contingencies or leaks due to breakage of any of the stove parts. The shell 13^a is then continued upwardly as a duct 39 and has at its upper extremity a 120 mouth 40 leading into the compartment 36, again being covered by a screen 41. These various screens 7, 38 and 41 serve the same purpose as the screen in the familiar miner's lamp. The heat given off by the stack 11 is 125 also taken advantage of to heat the air in the duct 13^a.

It will be seen that in this structure of Figs 6 and 7 the air in the compartment 36 is heated by the stove 1 without having the 130

flame or fire portion of the stove communicate in any way with the interior of this compartment 36. The duct 13^a is likewise provided with an inwardly extending mouth 42 to accommodate the ash pit door 8. In this manner it is safe to heat the interior of the compartment 36 through the direct agency of a coal stove without the attending danger of explosions. This stove as shown 10 in Figs. 6 and 7 may then also desirably be regulated the same as the stove shown in Figs. 1 to 5 inclusive is regulated. Screen 10^a protects the opening for the damper 11.

From what has been described the nature 15 of my invention will be clear to those skilled in the art. Having however thus described two forms which my invention may take, what I claim as new and desire to secure by Letters Patent is:—

20 1. A device of the character described comprising a fuel burning stove having a grate, a shell surrounding said stove forming a clear channel between said shell and the outer wall of said stove extending substantially throughout the full vertical length of said stove, said channel being substantially fully open at the bottom and at the top to thereby afford an unobstructed passage for an air current upwardly through said channel to thereby heat the air current passing through said channel and cause circulation of the air in the compartment where said device is placed, regulating means for said stove, and thermal means responsive to the 25 temperature of the air in said channel for controlling said regulating means, said thermal means comprising a fluid chamber around the top edge of the shell, an expandible diaphragm connected to said chamber and means connecting the diaphragm to the regulating means.

20 2. A device of the character described comprising a fuel burning stove having a grate, a shell surrounding said stove forming a clear channel between said shell and the outer wall of said stove extending substantially throughout the full vertical length of said stove, said channel being substantially fully open at the bottom and at the top to thereby afford an unobstructed passage for an air current upwardly through said channel to thereby heat the air current passing through said channel and cause circulation of the air in the compartment where said device is placed, regulating means for said 35 stove, thermal means responsive to the temperature of the air in said channel for controlling said regulating means, and means for adjusting the relationship between said thermal means and said regulating means,

said thermal means comprising an air chamber substantially surrounding the stove, an expandible diaphragm connected to said chamber and means connecting the diaphragm to the regulating means.

65

3. A device of the character described comprising a fuel burning stove having a grate, a shell surrounding said stove forming a clear channel between said shell and the outer wall of said stove extending substantially throughout the full vertical length of said stove, said channel being substantially fully open at the bottom and at the top to thereby afford an unobstructed passage for an air current upwardly through said channel to thereby heat the air current passing through said channel and cause circulation of the air in the compartment where said device is placed, regulating means for said stove, and thermal means within the air current in said channel and responsive to the temperature of the air in said channel for controlling said regulating means, said thermal means including an air chamber surrounding the stove and an expandible and retractable pneumatic device for operating said regulator.

75

4. A device of the character described comprising a fuel burning stove having a grate, a shell surrounding said stove forming a clear channel between said shell and the outer wall of said stove extending substantially throughout the full vertical length of said stove, said channel being substantially fully open at the bottom and at the top to thereby afford an unobstructed passage for an air current upwardly through said channel to thereby heat the air current passing through said channel and cause circulation of the air in the compartment where said device is placed, regulating means for said stove, thermal means within the air current in said channel and responsive to the temperature of the air in said channel for controlling said regulating means, and means for adjusting the relationship between said thermal means and said regulating means, said thermal means including an air chamber substantially surrounding the stove and an expandible and retractable pneumatic device communicating with the chamber and adapted to actuate the regulator.

95

In witness whereof I hereunto subscribe my name this 12th day of January, A. D. 1917.
